Filed Apr. 22, 1970, Ser. No. 22,555

Term of patent 14 years

Int. Cl. D6—01

U.S. Cl. D15—1

FIG. 1 is a perspective view of a child's seat showing my new design, with the parts thereof in one position of operation;

FIG. 2 is a side elevational view of the child's seat, taken from the left hand side of FIG. 1, and showing the parts thereof in a second position of operation;

FIG. 3 is a rear elevational view of the seat as shown in FIG. 2; and

FIG. 4 is a sectional view taken substantially along line 4—4 of FIG. 3.

I claim:

The ornamental design for a child's seat, substantially as shown and described.
